UNITED STATES PATENT OFFICE

102,163

DESIGN FOR A TENNIS RACKET OR SIMILAR ARTICLE

Horace W. Hall, Newton, Mass.

Application May 23, 1936, Serial No. 62,799

Term of patent 14 years

To all whom it may concern:

Be it known that I, Horace W. Hall, a citizen of the United States of America, residing at Newton, in the county of Middlesex and Commonwealth of Massachusetts, have invented a new, original, and ornamental Design for a Tennis Racket or Similar Article, of which the following is a specification, reference being had to the accompanying drawing, forming a part thereof.

The characteristic feature of my design resides in the handle, including the configuration of the laminae comprising the face pieces on each side of the racket extending from the lower portion of the head to the gripping portion of the handle as shown.

I claim:

The ornamental design for a tennis racket or similar article substantially as shown and described.

HORACE W. HALL.
